ABSTRACT OF THE DISCLOSURE

A crimping apparatus comprising a frame, a heated wheel rotatably attached to said frame and having two rows of peripheral dents having openings in the sides thereof and a peripheral groove positioned therebetween; a plurality of pins positioned in the said openings of adjacent dents; and endless crimping means adapted to engage said dents in said sprocket and having such diameter as to set within the said peripheral groove so as to pass over said pins; a tension regulating roller for pressuring said crimping means; a drive roller for guiding said crimping means around said wheel whereby material to be crimped is passed between said crimping means and said pins.

This invention relates to improvements in crimping devices. In one aspect this invention relates to a crimping apparatus highly desirable for crimping fiber glass. In another aspect this invention relates to a method for increasing the residence time and crimping pressure upon textile material being crimped without causing any crushing or damage to the material.

In the past, many and various types of crimping devices for crimping various substances have been developed but insofar as we are aware these formerly known devices were not as efficient or desirable in connection with the crimping of fiber glass materials. The apparatus of the subject invention is particularly adaptable to crimping glass yarns. Glass fibers exhibit a readiness to become abraded when either crushing pressure or frictional force is exerted thereupon.

With the foregoing in mind, it is an object of the instant invention to provide a crimping apparatus which eliminates any crushing of the material during the crimping operation;

Another object of this invention is to provide a crimping apparatus capable of permitting the use of high pressures without the subsequent shearing or abrading of the filaments being crimped;

Yet another object of this invention is to provide a crimping apparatus which substantially increases the residence time of the material while being crimped;

A still further object of the invention is the provision of a crimping apparatus capable of automatically maintaining the material being crimped in alignment;

A still further object of this invention is to provide a crimping machine capable of handling bundles of fibers as well as individual fibers if so desired and in a single operation providing both vertical and lateral crimp or wave in the bundles;

A still further object of the present invention is the provision of a crimping apparatus which is simple in construction, highly durable, rapid in operation, and economical both to build and operate;

Other objects and many of the attendant advantages of this invention will be readily appreciated as the same become better understood by reference to the following detailed description which is to be considered in connection with the accompanying drawings wherein:

2

FIG. 1 is a side elevation view of a crimping apparatus embodying principles of the instant invention;

FIG. 2 is an enlarged isometric sectional view, somewhat diagrammatic in character showing the positioning of the yarn relative to the crimping components;

FIG. 3 is a plan view of the apparatus;

FIG. 4 is an isometric view of various shaped pins;

FIG. 5 is a side elevational view of a second embodiment of this invention embodying the principles thereof;

FIG. 6 is a side elevational view of a third embodiment of this invention;

FIG. 7 is a side elevational view of a fourth embodiment of this invention.

Briefly, this invention relates to a crimping apparatus comprising a frame; a wheel means rotatably attached to said frame and having dents along the periphery thereof; heating means associated with said wheel for controlling the temperature of said dents; an endless crimping means adapted to cooperate with said dents in said wheel whereby a material to be crimped is passed between said dents and said endless crimping means; tension means for pressuring said endless crimping means against the said dents in said wheel.

With reference to FIGS. 1 through 4, the apparatus comprises a frame structure 1. Journaled substantially centrally of the frame structure 1 is a wheel 3 having two rows of equally spaced dents 5 extending peripherally around the circumference thereof. Thus, the wheel 3 is substantially a relatively wide gear or sprocket wheel. The wheel can be heated externally by a heater 4 placed in the area of the dents as shown in FIG. 1, or the interior of the wheel can be hollow inside of which there can be placed a plurality of heating elements (not shown). Such means for providing sufficient heat to the dents 5 are conventional and form no part of the inventive concept described herein.

A drive roller 7 is also journaled on frame 1 a predetermined distance from said wheel 3. The drive roller 7 is connected to a suitable source of power (not shown).

Trained over the drive roller 7 and the crimping wheel 3 is an endless crimping element 9. This endless crimping element in FIGS. 1-3 is made up of a series of cross rods 11 spaced apart in keeping with the pitch of dents 5 on wheel 3, and of such diameter as to seat well within the spaces between adjoining dents. The rods 11 are linked together in any suitable fashion as shown in FIGS. 2 and 3.

Pins 13 are rotatably positioned between pairs of adjacent dents 5, that is, a pin 13 connects with a dent on the inside of the wheel 3, whereby it traverses a peripheral groove to be more fully described hereinbelow. One method for rotatably supporting these pins between the teeth 5 is to provide apertures or openings 15 substantially near the crest of dents 5 into which the pins are positioned.

These pins can assume any shape desired and as shown in FIG. 4 they can be cylindrical, rectangular, triangular, hexagonal or the like. The choice of shape would depend on the crimp configuration desired in the yarn being textured.

A groove 17 is positioned around the periphery of the wheel between the two rows of dents 5. This groove provides a guide for fiber 2 during its passage between the rods 11 and the pins 13.

In operation, fiber, preferably fiber glass 2, is introduced from pin 18 through guide means 19 into the groove 17. The fiber 2 passes over rods 11 and under pins 13. The drive roller and tension regulator means 7 is actuated by a suitable power means (not shown) in order to rotate wheel 3. As the wheel 3 rotates the fiber is depressed between rods 11 and pins 13. The fiber is passed around the

circumference of the wheel 3 which increases its residence time. The pins 13 cooperate with the rods 11 to provide a cushioning effect thereby enabling an equal stress distribution to be provided to the fiber being crimped. As shown in FIGS. 1 and 2 this action will produce a V crimp formation in the fiber as the pins in this embodiment are cylindrical in shape.

Ordinarily, there will be sufficient pressure exerted by the crimping element 9 on the yarn 2 to effectuate a crimp therein; however separate, tension regulator means such as idler rollers 29 and 31 operatively connected to a spring biasing means 32 and 34 respectively can be employed to increase the pressure on the crimping element 9 when necessary.

In the embodiment described in FIGS. 1-4 the material construction of either the rods 11 or the pins 13 is not critical. The rods and pins can be formed of any suitable material so long as it provides sufficient rigidity to enable sufficient pressure to be exerted on the yarn to permit the crimping thereof. Suitable material may be wood, artificial resins, rubber, or the like. Both the rods and the pins may be made of the same or dissimilar material.

The crimped fiber 2 exits from the wheel 3 where it then passes through a guide means 21 to a suitable take-up device (not shown).

A second embodiment of this device is shown in FIG. 5. In this embodiment the crimping element 9 comprises a belt 23 in lieu of the rods 11 and pins 13. The belt 23 contains dents 24 which engage dents 25 in wheel 27. Fiber 28 is introduced through guide means 40 between the belt 23 and dents 25 on wheel 27 from supply source 26. The device according to this embodiment achieves equal stress distribution over the surface of the fiber through the careful selection of the materials for forming the belt 23 and the wheel 27. The belt is made of a substantially resilient material and the wheel of a substantially nonresilient material. Suitable materials are described in U.S. Patent No. 3,325,987.

The belt is in contact with the wheel over approximately half of its circumference thereby substantially increasing the residence time of the fiber during the crimping operation. Other conventional gear crimping devices exhibit point-to-point contact which gives a relatively short residence time to the yarn which is being crimped. The wheel 27 along with dents 25 are heated internally whereby the fiber 28 is initially more easily deformed and also more easily set in the crimped configuration than would be the case if it were being crimped by point-to-point contact as taught under prior art teachings. Since the dents 24 in belt 23 do not make a positive fit between the dents 25 in wheel 27, there will always be some clearance for the yarn to shift without shearing or breakage of filament when pressure is applied under high temperatures. The belt passes the crimped fiber 28 from wheel 27 through guide means 42 to a suitable take-up device (not shown). The belt then continues in a closed loop over idler rolls 29, 30 and 31 respectively. The idler rollers 29 and 31 are positioned approximately 180° apart adjacent wheel 27. A suitable drive means 41 rotates wheel 27 in a clockwise direction so as to drive belt 23 in a counter clockwise direction around wheel 27.

It will be understood that in this embodiment the shape of the dents in both the wheel 27 and in the belt 23 can be varied to provide different shaped crimps in the fibers.

With reference to FIG. 6 an embossing roll 34 is suitably positioned above idler roll 31 on arm 36. Arm 36 is pivoted on a suitable support 38. The embossing roll 34 through any suitable means is intermittently brought into engagement with idler roll 31 in order to re-emboss the dents 24 in belt 23 passing therebetween. By this means the amplitude of the crimps in the yarn being treated are maintained substantially uniform.

FIGURE 7 depicts yet another embodiment of this invention. In this embodiment belt 23 passes over wheel 27,

5 idler roller 44 and idler roller 45 in its endless path. A tension band 43 composed of any suitable material such as steel, hard rubber or the like passes over belt 23 and around wheel 27 and pulley 46. This band increases the tension on belt 23 so as to provide sufficient crimping pressure in the instances when the pressure exerted by idler roll 31 is not sufficient to provide a crimp in the material being textured. A tension adjusting means 47 such as a belt tightening screw is operatively connected with pulley 46 whereby the tension on belt 23 can be regulated.

In summation the advantages garnered by one employing the method and apparatus of this disclosure are an increased residence time during the crimping operation because of the elimination of point-to-point contact and also a minimum amount of crushing because of the movement of the yarn around the pins in the first embodiment and the use of a resilient belt crimping means in the second embodiment. These devices permit easy control of crimp amplitude by a slight modification of the chain release in embodiment 1 and in the height of the dents 24 in the belt 23 in embodiment 2.

Obviously many modifications and variations of the present invention are possible in the light of the above teachings. It is therefore to be understood that the invention may be practiced otherwise than as specifically described herein.

What is claimed is:

1. A crimping apparatus comprising a frame; a wheel means rotatably attached to said frame and having dents along the periphery thereof; heating means associated with said wheel for controlling the temperature of said dents; an endless crimping means adapted to cooperate with at least two of said dents in said wheel whereby a material to be crimped is passed between said dents and said endless crimping means; an endless tension band positioned around said endless crimping means for pressuring said endless crimping means against the said dents in said wheel and a tension regulator means operatively connected to said band for regulating the tension thereof.
2. A crimping apparatus according to claim 1 wherein said endless crimping means includes a substantially resilient belt having dents suitably positioned therein to cooperate with said dents positioned in said wheel.
3. A crimping apparatus according to claim 1 wherein tension regulating means include a belt tightening screw.
4. A crimping apparatus according to claim 1 wherein said tension regulator means includes a first idler means positioned adjacent to said wheel; a second idler means positioned adjacent to said wheel approximately 180° from said first idler means; a third idler means positioned with respect to said wheel, to said first and to said second idler means so as to form a closed loop for said endless crimping means passing around said wheel means over said first idler means over said second idler means and back to said wheel means.
5. A crimping apparatus according to claim 4 further including a drive means associated with said wheel.
6. A crimping apparatus according to claim 5 further including an embossing means associated with said first idler means whereby said crimping belt is reimbossed as it passes over said first idler means.
7. A crimping apparatus according to claim 6 further including disengaging means associated with said embossing means for disengaging said embossing means from said first idler means.
8. A crimping apparatus comprising a frame; a wheel means rotatably attached to said frame and having two rows of peripheral dents, said dents having openings in the sides thereof, and a peripheral groove located between said two rows of dents; heating means associated with said wheel means for controlling temperature of said dents; a plurality of pins positioned in the said openings of adjacent dents whereby said pins traverse said groove; an endless crimping means adapted to engage said dents in said wheel means and having such diameter

as to seat within the said peripheral groove so as to pass over said pins; a tension regulator means for pressuring said endless crimping means against the plurality of pins.

9. A crimping apparatus according to claim 8 wherein said tension regulator means include a first spring biased roller operatively connected to said wheel and a second spring biased roller operatively connected to said wheel a predetermined distance from said first roller.

10. A crimping apparatus according to claim 6 including a guide means for guiding said endless crimping means around the wheel whereby material to be crimped passed between the endless crimping means and the pins.

11. A crimping apparatus according to claim 10 wherein said guide means includes a drive roller positioned apart from said wheel whereby said crimping means forms a closed loop in passing over said wheel and said drive roller.

12. A crimping apparatus according to claim 8 where-

in said endless crimping means includes a plurality of rods, said rods being linked together so as to sit between adjoining dents in said wheel means.

13. A crimping apparatus according to claim 8 where in said pins have a cylindrical shape.

14. A crimping apparatus according to claim 8 where in said pins have a hexagonal shape.

15. A crimping apparatus according to claim 8 where in said pins have a rectangular shape.

16. A crimping apparatus according to claim 8 where in said pins have a triangular shape.
